UNITED STATES PATENT OFFICE.

JONAS T. LAGERGREN, OF ERIE, PENNSYLVANIA.

COMPRESSOR.

Application filed June 12, 1925. Serial No. 38,656.

The present invention relates to compressors specifically adapted for use with refrigerating apparatus wherein a refrigerant, such as ammonia or other suitable gas, is compressed in the compressor, then cooled and liquefied in a condenser and liquid container, and finally expanded in a refrigerating room to produce useful refrigeration.

One object of the invention is to provide a novel arrangement of compressor parts with a view to compactness and efficiency. Another object is to provide a novel oscillating cylinder for the compressor whereby the friction during operation is greatly reduced and high speed and efficiency may be had. Another object is to provide for the firm seating of the cylinder upon the wall wherein the inlet and outlet ports are located and over which the cylinder oscillates. These and other objects of my invention will be more readily understood upon reference to the following detailed description, taken in connection with the accompanying drawings, and the scope of the invention will be particularly pointed out in the appended claims.

In said drawings, Fig. 1 is a central vertical section of a refrigerating apparatus employing a compressor constructed and arranged in accordance with the present invention, the driving motor being omitted; Fig. 2 is a plan view of the same, some of the conduit connections at the top being shown in section taken on a plane indicated by the line 2—2 of Fig. 1; Fig. 3 is a horizontal section of the same, the plane of section being indicated by the line 3—3 of Fig. 1; Fig. 4 is an elevational view showing certain parts in full and compressor parts in section, the plane of section being indicated by the line 4—4 of Fig. 1; Fig. 5 is a detail sectional view of a modification illustrating the opening at the upper end of the cylinder bore as somewhat restricted; Fig. 6 is a partial sectional elevation, taken on a plane indicated by the line 6—6 of Fig. 1, illustrating particularly means by which the cylinders may be maintained tight upon their seats; Fig. 7 is an elevation illustrating a modified arrangement by which the cooling tank capacity is enlarged by connection with an auxiliary tank containing a supply of cooling liquid; Fig. 8 is an elevation illustrating particularly the gauges and safety valve at the top of the cooling tank; Fig. 9 is a diagrammatic view illustrating

the position of the driving motor, the connections for supplying the refrigerant to a cooling room, and the electrical control of the driving motor by a thermostat; and Fig. 10 is an elevation of a modified form of cooling tank. Throughout these views like characters refer to like parts.

Referring to the drawings in detail, A designates the cooling tank, B the compressor within the tank, C the condenser above the compressor, D the liquid container within the condenser coil, and E a chimney surrounding the condenser and container, and operative to circulate the cooling liquid within the tank. In operation, the refrigerant in the form of a gas enters the compressor by way of the supply conduit connections F and G. From the compressor the refrigerant now compressed and heated passes to the coil of the condenser by way of the conduits H and I. After passing through the coil of the condenser and giving up some of its heat, the refrigerant is led from the lower end of the condenser coil C by conduit J to the upper end of the liquid receiver D, wherein it appears in liquid form. From the lower end of the receiver D the liquid refrigerant passes by way of conduits K and L from the apparatus.

The cooling tank A is preferably an open ended upright tubular tank having a circular wall 10 of metal mounted upon a base 11 of cast iron or other suitable material. The compressor B is of special construction intended for high speed operation. It is provided with a horizontal crank shaft 13, having cranks 14 which are directly connected to the lower ends of pistons 15 which extend upward into the bores of oscillating cylinders 16 which are mounted to move to and fro upon arcuate casing walls 17, which serve as bearings or seats for the cylinders 16. The crank shaft is mounted in suitable bearings 18 and 19 formed respectively in the casing walls 20 and 21. These walls form the ends of the compressor casing and are joined to an intermediate member 23 having a lower portion 22 which serves as a base for the compressor structure. The casing member 23 includes the wall 17, previously referred to. The base portion 22 is secured to the base 11 of the tank A in any suitable way, as by means of the screw bolts 25. The other parts of the casing of the compressor B are secured together in any suitable way. The structure of the casing is such that the crank shaft is

located in a lubricant compartment 26 and, preferably, the level of the lubricant, which is ordinarily a suitable oil 27, is high enough to engage the crank shaft and the cranks, 5 and as they are rotated the oil is dashed up against the moving parts so as to fully lubricate them. The upper end of the casing 23 is provided with an inlet port 28 which is in direct communication with the supply conduit 10 G. The same part of the casing is provided with an outlet port 29 which is in direct communication with the conduit H. The latter port is controlled by a check valve 31. In 15 operation as the piston 15 moves downward upon the suction stroke, the cylinder 16 is in position to bring the open end 32 of the bore of the cylinder into communication with the inlet port 28. In this way a charge of the 20 gaseous refrigerant is drawn into the cylinder. Then as the cylinder oscillates and the piston begins its compression stroke the open end 32 has passed out of communication with the inlet port 28 and is brought into communication with the outlet port 29. The 25 upward movement of the piston compresses the gas and overcomes the spring of the check valve 31 and the compressed gas is thereupon driven through the conduit H. It will be noted that the upper end 32 of the bore of 30 the cylinder permits the gas, when being compressed by the piston 15, to exert pressure directly upon the wall 17 of the casing instead of upon an end wall of the cylinder. This is an important feature of my invention, for by this arrangement the friction of 35 the cylinder 16 upon its seat 17 is greatly reduced. In many prior art devices, the compression acts solely upon the walls of the cylinder and in this way greatly increases the 40 pressure of the cylinder upon the surrounding bearing wall of the casing. The hole made in drilling the inlet port 28 is, in the embodiment shown, closed by the threaded plug 33. Likewise, in the case of the check 45 valve 31, the stem of the valve travels up and down in a bore in the plug 34, which is threaded into a sleeve 35, in turn held in an opening in the casing by a cap or plug 36.

The open end 32 of the bore of the cylinder 50 is, in the embodiment shown in Fig. 4, of the same diameter as the rest of the bore. Thus the pressure exerted upon the cylinder itself during the compression stroke is not upward, but lateral. In some instances, it may be de- 55 sirable to use some of this pressure to provide for the firm seating of the cylinder 16 upon its seat 17. Where this is desired the open end 32 of the bore of the cylinder may be replaced by a restricted open end 32', 60 such as shown in Fig. 5. There, the overhanging ledge 37 receives pressure upon its under side which tends to force the cylinder 16 upward. The extent of this pressure will depend upon the extent of the overhang of 65 the ledge 37. This may be varied as desired.

Preferably, however, the cylinder 16 in each instance is caused to firmly seat itself by the employment of compression springs 38 which, in each instance, act against a fixed part 39 of the casing and lug 41 upon the 70 sides of the cylinder 16. These lugs are apertured for the passage of a guide rod 42 which at its upper end enters a hole in the casing, and at its lower end is provided with a head 43 which is screwed into a threaded 75 aperture in the portion 39 of the casing. The lower edge of the lug 41 is in each instance beveled so as to provide a knife edge 44. The coiled spring in each instance bears at its lower end against the casing and at its 80 upper end against a washer 40 which, in turn, bears upon the knife edge 44. The compressive force exerted by the springs 38 is just sufficient to nicely seat the cylinders 16, and to provide efficient and satisfactory 85 operation.

For the purpose of supplying lubricating oil to the chamber 26, I preferably connect to the upper side of the casing 23 two stand pipes 45 and 46. These communicate at their lower ends with the casing 26 through suitable passages, such as the passage 47 shown in Fig. 4. The upper end of each of these stand pipes extends above the level of the cooling liquid and is provided with a closing 90 cap 48. When it is desired to supply lubricant to the chamber 26, one, or both, of these caps 48 is removed and the lubricant poured down through the pipe into the chamber. Besides serving as a conduit for 95 supplying the lubricant, these stand pipes receive the foam and vapor from the oil produced by the churning action of the cranks operating in the crank chamber 26, and as the same rises up in these pipes it is 100 condensed and returned. By this arrangement high pressure within the chamber 26, due to the churning of the lubricant, is eliminated.

The shaft 13 of the compressor extends 110 through an aperture in the tank wall 10 and is driven by a motor located outside of the tank. Preferably, an electric motor 49 is used for this purpose, and its shaft is connected to the end of the shaft 13 by coupling 115 51. The motor and tank A are preferably mounted upon a common base 52. For this purpose the base 11 of the tank is provided with suitable openings 50 through which bolts may be passed into the base 52 to secure the tank in place. A seal is provided 120 for the shaft 13 to prevent the escape of any gas from the chamber 26 along the shaft to the outside of the tank. This seal is made by using two sections of packing 53, 54 separated by a suitable spacing means such as a lantern 55. The packing 53 and 54 closely embraces the shaft 13 and the outer packing 54 is held in place by a gland 56 surrounding the shaft and fitted into the end of the 125 130

bore in the projecting member 57 through which the shaft 13 extends. The member 57 is preferably made integral with the end member 21 of the casing of the compressor, and is provided with a flange 58 at its outer end by which it is firmly secured to the tank wall 10 through the agency of an outer ring 59 and suitable securing means, such as the screws 61. The outer end of the gland 56 terminates in a head 60 which is firmly secured to the member 57 by bolts 60' which are threaded into tapped openings in said member. The space in which the lantern 55 is located is in communication with the lower end of a stand pipe 62, which is similar to the stand pipes 45 and 46 and is closed at its upper end by a cap 63. This stand pipe is filled more or less with oil or other suitable liquid, and by its employment static pressure is applied to the packing 53 and 54 at the lower end of the pipe, and in this way a firm seal is produced. Furthermore, any gas which may creep along the shaft 13 as far as the lantern 55 will at once pass upward through the oil in the stand pipe 62. None will pass beyond the packing 54 through gland 56 to the outside of the tank.

The condenser C is preferably a continuous coil of tubing supported by its connection at its upper end with the piping H and I. The conduit J which connects the lower end of the coil C with the upper end of the receiver D also serves to support the latter in its position within the coil. The receiver is also supported in part by the conduit K which is connected near its lower end and passes upward through the open end of the tank. Obviously, instead of relying upon the piping connections to support the condenser C and receiver D in place, other means might be employed. However, in practice, this is found sufficient. The chimney E preferably rests in part upon transverse members 64 which are secured to the casing 23 of the compressor B. The chimney may also rest in part upon the flanges of the elbows of the conduits G and H, as illustrated in Fig. 4. The lower end of the chimney, which is tubular, rests upon these cross members and flanges at its lower end, and is at its upper end held against tilting by one or more stays 65. It will be seen that as the water, or other cooling liquid, in the tank A, which normally practically fills the tank, being in the instance shown at the level 66, is heated by the compressed gas giving off its heat in the condenser C, it will move upward within the chimney E toward the top of the tank, being replaced by the cooler water toward the bottom of the tank. Thus a circulation will be established by which the water will pass upward within the chimney and downward outside of the same. This circulation will not only facilitate the cooling and liquefying of the compressed

gas, but will also tend to keep the high speed compressor B cool. In practice, the capacity of the cooling tank A is proportional to the capacity of the compressor, and the design is preferably such that the apparatus can be run for a predetermined period and develop a predetermined amount of refrigeration with the temperature of the cooling liquid in the tank kept within reasonable limits. In a design for a household machine, designed to run about two hours for producing a refrigerating effect equal to 25 pounds of ice, the single tank arrangement of Fig. 1 will be sufficient. Even where double that amount of refrigeration is required, it may be obtained by running the machine a couple of hours in the morning and then the same period in the evening. This will give the water or other cooling agent in the tank A sufficient time to cool off between the running periods. Of course, if desired, the tank A may be made much larger, and in this way a constant operation of the apparatus provided for. If, in other instances, the space available for the tank A is not sufficient for the amount of refrigeration required, then the tank A may be associated with an auxiliary tank A' located in any suitable place and connected by suitable piping or conduits 68 and 69, as illustrated in Fig. 7.

For the purpose of indicating the difference in pressure between the high pressure and low pressure sides of the apparatus, I provide a high pressure indicator 71 connected with the conduit H through an extension 72, and a low pressure indicator 73 connected with the conduit G through an extension 74. The extension pipes 72 and 74 are connected by cross conduits 75 and 76 to a safety valve 77. The operation of this valve is the usual one. When the pressure on the high pressure side becomes too great, the valve 77 opens to bring about a reduction of pressure upon the high pressure side.

When the apparatus is not in use, provision must be made for draining it. This is accomplished by outlet passages 78, 79, and 81, located in the base 11 of the tank A. The passage 78 merely extends far enough into the metal of the base 11 to pass the outer wall 10, and then the same communicates with a vertical passage 82 which opens directly into the interior of the tank A. Through the passages 82 and 78 the water or other cooling liquid within the tank A may be drained off. Likewise, the passage 79 extends far enough into the metal of the base 11 to open up communication with the crank chamber 26 of the compressor, as illustrated more clearly, perhaps, in Fig. 4. Through this passage then, the crank case may be completely drained. The remaining passage 81 extends through the metal of the base 11 to a point directly beneath the

lower end of the drain pipe 83 with which it communicates by a short upward turn. The pipe 83 is connected through suitable coupling flanges 84 to a transverse pipe 85 which communicates with the liquid receiving tank D. Through the pipes 85 and 83 and the passage 81, it is therefore possible to drain the liquid receiver D. The outer ends of these conduits 78, 79, and 81, are closed by screw caps 86, 87, and 88, respectively, or by proper stop valves.

The various conduits F, G, H, I, and K, are connected together in the embodiment shown by couplings formed in each instance 15 of blocks in which the ends of the conduits are firmly seated, and then these blocks are secured together by bolts. Since these couplings are practically the same in all instances, I have designated the blocks generally as 91, and the connecting bolts as 92. Obviously, other connecting means might be employed.

In the use of my refrigerating apparatus, the refrigerant may be variously employed 25 after passing from the tank A. Many arrangements for utilizing the same are well known. However, for the purpose of illustration, I have shown in Fig. 9 a complete arrangement wherein the refrigerant passes 30 from the tank A through conduit L to a refrigerating chamber R in which a cooling coil 93 is located; it is supplied with the refrigerant through an expansion valve 94, and the return end of the coil 93 is connected 35 to the conduit F which leads the gas back to the apparatus in the tank A. The expansion of the cooled and condensed refrigerant as it passes through the valve 94, which may be either automatically or manually operated, 40 causes the objects in the chamber R to give up heat, and thus the desired refrigeration is obtained. In the case shown, a thermostat 94' in the chamber R controls the circuit of the motor 49 to start and stop the same, according 45 to the requirements of the temperature in the chamber R. As here shown, the motor 49 is an electric motor supplied with current from mains 95 and 96, the current passing through the contacts of a switch 50 97, and through conductors 98 and 99, the conductor 98 in this instance being the one shown in circuit with the thermostat 94'. Obviously, various circuit arrangements 55 might be provided for the control of the motor, and this would be true whether the motor employed were an electric motor, or a motor relying upon other energy for its actuation.

With reference to the circulation of the 60 water or other cooling liquid within the tank it is clear that the circulation facilitates the cooling, which occurs both by conduction through the tank walls and by evaporation or convection at the water's surface. For 65 the latter purpose the top of the tank is open

so as to leave the water in direct contact with the air. If desired the tank may be specially shaped so as to increase the area of the surface of the water thus exposed. Thus, in Fig. 10 I have illustrated a tank A² of the 70 same general construction as the tank A except that its upper end is bell-mouthed, made so by curving the upper portion 100 of the wall outward. By filling the tank A² almost full, say to the water level 101, a large superficial cooling area is provided by the surface of the water. With a tank of this construction the water is more rapidly cooled and the capacity of the apparatus is thereby increased. 80

It will be clear from what has been said heretofore that with the employment of the thermostat 94' in the circuit arrangement of Fig. 9, or in any other equivalent circuit arrangement, the apparatus will operate automatically as the temperature changes in the space R may require. The periodic operation of the apparatus, as for instance a couple of hours in the morning and then the same period in the evening, heretofore referred to, would be the method of operation where automatic control by a thermostat was not necessary or desirable. 90

Although the positions of the condenser C and liquid receiver D are shown and described as vertical, yet the same in some installations may be inclined to the vertical. Obviously considerable change could be made in this respect without departing from the mode of operation of the apparatus. 95

It will be clear that in carrying out my invention still further alterations and modifications may be made in the structures illustrated without departing from its spirit and scope. I therefore do not wish to be limited 100 to the details herein disclosed, but aim to cover all such alterations and modifications as come within the spirit and scope of my invention, by the terms of the appended 105 claims. 110

What I claim as new and desire to secure by a patent of the United States is:

1. A compressor including a casing, an oscillating cylinder mounted therein, a piston reciprocable in the bore of said cylinder, 115 ports in the casing wall upon which said cylinder oscillates cooperating with the open end of said bore, said open end permitting the pressure within the cylinder bore during the compression stroke of said piston to act directly upon said casing wall wherein said ports are located, and means acting between said cylinder and a portion of said casing opposite said ports to yieldingly seat said cylinder upon said ported wall. 120

2. A compressor including a casing, an oscillating cylinder mounted therein, a piston reciprocable in the bore of said cylinder, 125 ports in the casing wall upon which said cylinder oscillates cooperating with the

open end of said bore, said open end permitting the pressure within the cylinder bore during the compression stroke of said piston to act directly upon said casing wall wherein said ports are located, and means for yieldingly holding said cylinder against said ported casing wall as said cylinder oscillates.

3. A compressor including a casing, an oscillating cylinder mounted therein, a piston reciprocable in the bore of said cylinder, ports in the casing wall upon which said cylinder oscillates cooperating with the open end of said bore, said open end permitting the pressure within the cylinder bore during the compression stroke of said piston to act directly upon said casing wall wherein said ports are located, and means for causing said cylinder to press snugly against said ported casing wall as said cylinder oscillates, said means including compression springs acting between fixed portions of said casing and lugs on said cylinder.

4. A compressor including a casing, an oscillating cylinder mounted therein, said cylinder having oppositely extending lugs, guide rods extending through openings in said lugs, compression springs acting between said lugs and casing to force said cylinder yieldingly against one portion of the casing wall upon which said cylinder oscillates, and ports in said portion cooperating with the bore in said cylinder.

5. A compressor comprising a cylinder, a piston reciprocable in the bore of said cylinder, a member having ports cooperating with the open end of said bore, said cylinder and member being relatively movable, and means for yieldingly holding the open end of said cylinder against said ported member to maintain the open bore and the ports in operative relation as the cylinder and member are relatively moved.

In witness whereof, I hereunto subscribe my name this 9th day of June, 1925.

JONAS T. LAGERGREN.
